UNITED STATES PATENT OFFICE.

WILLIAM P. CLIFFORD, OF OTTUMWA, ASSIGNOR TO DAVID W. TEMPLETON,
OF FAIRFIELD, AND THE WESTERN MACHINE WORKS, OF OTTUMWA,
IOWA.

OAT-EXTRACTOR FOR GRAIN-SEPARATORS.

SPECIFICATION forming part of Letters Patent No. 392,783, dated November 13, 1888.

Application filed March 10, 1886. Serial No. 195,874. (No model.)

To all whom it may concern:

Be it known that I, WILLIAM P. CLIFFORD, a citizen of the United States, residing at Ottumwa, in the county of Wapello and State 5 of Iowa, have invented a new and useful Oat-Extractor for Grain-Separators, of which the following is a specification.

The object of the invention is to provide means for separating oats from the grain in a 10 thorough and efficient manner.

The invention consists in the peculiar construction and arrangement of parts, as herein-after fully described, and pointed out in the claims.

15 Figure 1 is a side elevation of my improvement. Fig. 2 is a longitudinal vertical section of the same; and Fig. 3 is a sectional end elevation, part of the cylinder being broken away.

Referring to the drawings, A represents a 20 casing provided with the inclined apron a and screen a², the screen being inclined in an opposite direction to the apron and projecting through the side of the casing.

B is a hopper projecting into the casing and 25 provided with the central discharge-opening, b, in the inner side of its lower part, and opposite the discharge-opening of the hopper is placed the oat-extracting cylinder C, which is attached to the shaft D.

30 The cylinder C is composed of three or more disks, d, attached to the shaft; staves d², attached to the rims of the disks and forming a wooden shell, and the indented sheet-metal plate d³. The wooden shell is first turned to 35 a true cylinder, and then the metal plate d³ is applied. The indentations in the sheet-metal plate are of such a size as to receive kernels of wheat and carry them over the top of the cylinder, while the kernels of oats cannot enter 40 the said indentations. Several plates d³, with indentations of different sizes, are to be provided, so that different plates can be used for grains having kernels of different sizes.

The journals of the shaft D revolve in bearings attached to the levers E, the inner ends 45 of which are pivoted to the casing A. The outer ends of the levers E project beyond the casing and are perforated to receive the hand-screws F, which are swiveled to the ends of the 50 said levers. The hand-screws F pass through

screw-holes in brackets e, projecting from the casing, so that the cylinder can be adjusted for decreasing or increasing the discharge-opening of the hopper by adjusting the hand-screw F. The hand-screws F can be locked in place 55 when adjusted by lock-nuts f, placed upon them, and which can be turned down against the brackets e.

To one end of the shaft D is attached a pulley, d⁵, to receive a belt from any convenient 60 power. To the other end of the shaft D is attached the pulley d⁴ to receive the belt e², which also passes around the pulley g on the journal of the cylindrical brush G. The journals of the brush G revolve in bearings in the lower 65 ends of hangers g², which pass up through the top of the casing and have their ends screw-threaded to receive the hand-nuts g³, so that by adjusting the said nuts g³ the brush G can be adjusted to work at any desired nearness to 70 the surface of the extracting-cylinder, so as to brush back any kernels of oats from the surface of the said cylinder, and thus prevent the oats from being carried over the cylinder. In 75 the side of the casing, in rear of the wall of the hopper and above the opening b therein, are formed openings a³, from which lead the spouts a⁴.

The operation is as follows: The grain (wheat and oats) being fed in the hopper B will pass 80 out through the opening b therein, and the kernels of wheat will be taken up by the cylinder and delivered on the other side thereof, leaving the oats in the space between rear portion of the hopper and brush and cylinder. When 85 a sufficient quantity of oats has collected in the said space to reach the openings a³ in the side of the casing, they escape through the said openings and are guided by the spouts a⁴ into some suitable receptacle. The kernels of wheat 90 that are carried over the cylinder fall upon the apron a and pass from thence onto the screen a², the cockle and other small seeds passing through the screen, while the grains of wheat slide down and pass out of the casing. 95

Having thus described my invention, what I claim, and desire to secure by Letters Patent, is—

1. In a grain-separator, the combination, with a casing having openings in its sides, of 100

the hopper B, having the central discharge-opening, *b*, the oat-extracting cylinder C, and the brush G above the cylinder, substantially as herein shown and described.

5 2. In a grain-separator, the combination, with the casing A, provided with the brackets *e*, and the hopper B, having the central opening, *b*, of the pivoted levers E, the cylinder C,

journalized in bearings carried by said lever, the hand-screws passing through the said levers *ic* and brackets, and the lock-nuts *f* on the screws, substantially as herein shown and described.

WILLIAM P. CLIFFORD.
